UNITED STATES PATENT OFFICE.

REINHOLD MAMERS, OF BROOKLYN, NEW YORK.

TOOL-HOLDER.

1,371,799.

Specification of Letters Patent.

Patented Mar. 15, 1921.

Application filed May 18, 1920. Serial No. 382,391.

To all whom it may concern:

Be it known that I, REINHOLD MAMERS, a citizen of the United States, residing at Brooklyn, in the county of Kings and State 5 of New York, have invented new and useful Improvements in Tool-Holders, of which the following is a specification.

This invention relates to a tool holder for holding cutting tools and the like and 10 the principal object of the invention is to provide a spring connection between the tool carrying part of the holder and the rest of the holder so that the tool may yield slightly under the action of the work piece.

15 Another object of the invention is to provide means for adjusting the spring action so as to make it more or less to suit the conditions under which the tool is being used and the work being done.

20 A further object of the invention is to provide means whereby this yielding movement will be practically eliminated when desired.

It is thought from the foregoing description that the advantages and novel features 25 of my invention will be readily apparent.

I desire it to be understood that I may make changes in the construction and in the combination and arrangement of the 30 several parts, provided that such changes fall within the scope of the appended claims.

Figure 1 is a side view of the device.

Fig. 2 is a longitudinal sectional view.

Fig. 3 is a bottom view.

35 Fig. 4 is an end view.

Figs. 5, 6 and 7 are detail views.

In these views 1 indicates the shank of 40 the holder and 2 the head thereof. This head is provided with a spring part 2' which is formed by a circular opening 3 and the slot 4 made in the head. This slot and opening divide the part 2' from the rest of the head excepting at the upper portion thereof so that this upper portion will act 45 as a spring to permit a certain movement of part 2', this movement increasing or decreasing the width of the slot 4. In order to increase the spring action I place a split

50 sleeve 5 of spring metal in the opening 3, this sleeve being held against turning movement by the screw 6. A recess 7 is formed in the lower part of the main part of the head 2 and an inclined hole 8 is formed in the lower part of the portion 2' for receiving 55 the cutting tool 9. This tool passes en-

tirely through the hole 8 and has its inner end located in the recess 7 in the main part of the head. The tool is clamped in position by means of the clamping bolt 10 which engages with a hole 11 formed in the part 60 2'. This bolt has a transverse opening 12 in its inner end through which the cutting tool passes and the outer end of the bolt is screw threaded to receive the nut 13 which holds the parts in position. By 65 means of this bolt and nut the cutting tool may be adjusted transversely in the holder. Where necessary spaced blocks may be used for properly adjusting the tool.

The lower part of the tool is provided 70 with a channel 14 in which is located a spring strip 15. The front end of this strip is bolted to the bottom of the part 2' while its other end is provided with a screw threaded socket 16 for receiving the adjusting bolt 17, these parts being so arranged that by screwing this bolt 17 one way or the other the strip 15 is moved longitudinally to control the tension of the spring part 2'. I prefer to enlarge the end carrying the socket 16 and to split it so as to make the diameter of the socket adjustable by means of the screws 18. This enlarged part fits in a recess 19 formed in the shank 1 adjacent the end thereof. 85

It will thus be seen that when the tool is acting against a work piece, such as that shown at 20, it will be yieldingly held against said work piece by the part 2'. The yieldability of this part 2' can be adjusted 90 by moving the strip 15 longitudinally by means of the bolt 17. If it is desired to practically prevent movement of the part 2' a bar or the like may be inserted in the lower end of the slot 4, the wall of which 95 is provided with a recess 4', and this bar will prevent downward and inward movement of the bar 2'. The spring action may also be adjusted by the use of spring sleeves, such as that shown at 5, of varying dimensions. 100

My invention provides lots of room for the cutter and it can be used for heavy and light work by controlling the spring action.

The opening 8 is of oblong shape as 105 shown and of course may be made of various sizes to fit the different sizes of tools or to receive several tools at the same time. The recess 7 is made of sufficient size as to permit the end of the tool to move freely 110

therein under the spring action of the holder. This recess 7 also permits a long cutter or tool to be carried by the holder.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A spring tool holder comprising a spring part for carrying the tool and means for adjusting the yieldability of this part, such means comprising a spring strip having one end connected with the spring part and means engaging the other end for adjusting the strip longitudinally.
- 20 2. A spring tool holder of the class described comprising a shank and a head, said head having an opening therein and a slot, said opening and slot dividing the head

into a main part and a spring part, means carried by the spring part for supporting the cutting tool, means for controlling the yieldability of said spring part, such means including a spring plate having one end connected with the spring part and means at the other end for moving said plate longitudinally.

3. A spring tool holder of the class described comprising a shank and a head, said head having an opening therein and a slot, said opening and slot dividing the head into a main part and a spring part, means carried by the spring part for supporting the cutting tool, means for controlling the yieldability of said spring part, such means including a spring plate having one end connected with the spring part, means at the other end for moving said plate longitudinally and a split spring sleeve located in the opening.

In testimony whereof I affix my signature. 45
REINHOLD MAMERS.
